UNITED STATES PATENT OFFICE.

LOUIS GRIMOND MACINTYRE, OF BROUGHTY FERRY, SCOTLAND.

SLIVER-LAP-FEEDING MECHANISM.

1,424,580.

Specification of Letters Patent. Patented Aug. 1, 1922.

Application filed November 6, 1920. Serial No. 422,157.

To all whom it may concern:

Be it known that I, LOUIS GRIMOND MACINTYRE, a subject of the King of Great Britain and Ireland, and a resident of Carbet 5 Castle, Broughty Ferry, in the county of Forfar, Scotland, manufacturer, have invented a certain new and useful Sliver-Lap-Feeding Mechanism, of which the following is the specification.

10 Where a continuous lap of sliver flowing at constant speed has to be delivered successively to a series of two or more machines, such for example as sliver balling machines such for example as that illustrated in my 15 Patent No. 1,404,623, dated January 24, 1922, it is necessary that the stream of sliver should be momentarily interrupted and the lap broken at that instant when a change over from one machine to another is taking 20 place, otherwise the lap will accumulate and lead to choking or irregularity of operation of the machine coming into use.

The invention has for its object to provide 25 simple and effective means for interrupting the flow of the sliver lap and for breaking it at the moment its delivery is diverted from one machine of a series to another.

According to the invention there is provided a pair of feeding rolls driven at a normal 30 surface speed slightly greater than that of the lap. Preceding these rolls is a gap in the shoot or equivalent device in or on which the sliver flows to the rolls and which is so proportioned and devised that a loop 35 of sliver may lie therein as hereinafter explained. In the train of gearing is a reverse mechanism adapted to be operated preferably automatically by that machine of the series being fed when that machine has 40 completed its operation and a change over to another of the series is about to take place. The pair of rolls, or one of them, is operated through clutch mechanism from this gearing, and the rolls are thus momentarily 45 stopped and reversed, the duration of their stoppage and reversal being controlled by a device in the reverse mechanism which rethrows the clutch and causes the rolls to be again driven in the direction for feeding 50 the lap.

The actual distance through which the rolls are reversed is preferably under the primary control of adjustable means independent of the reversing mechanism which, 55 while allowing free rotation in the forward direction, imposes a limitation upon the arc

through which the rolls may be turned in the reverse direction. The momentary reversal of the rolls not only causes definite breakage of the lap but also stops the flow 60 (the lap accumulating in the gap) for that brief period in which change over from one machine to the next in order takes place. By virtue of the increased surface speed of the feeding rolls over that of the lap, the 65 loop or festoon formed in the gap by the continued delivery of sliver during the period of stoppage and reversal is taken up before it is again necessary to break the sliver. 70

From the controlling rolls the sliver lap passes either to a conveyor which may be of belt type and which is reversed where there are two machines alternately operating, or to a swiveling or movable shoot from which 75 the lap is delivered to one of two or more machines.

An illustrative example of the carrying out of the invention is shown to some extent 80 diagrammatically on two accompanying sheets of explanatory drawings, Figure 1, Sheet 1, of which is an end view of the delivery and feeding rolls, Figure 2 a sectional plan of the reversing clutch controlling the 85 sliver breaking mechanism, and Figure 3 Sheet 2 a front elevation of the feeding rolls showing in outline the operating gear for the clutch.

In this example sliver is shown passing 90 from a pair of delivery rolls A¹, A² over a gap to a pair of feeding rolls B¹, B², mounted on shafts B³, B⁴ respectively, with the latter of which the sliver breaking mechanism is associated, and thence over a guide band C to a second set of feeding rolls D¹, 95 D². The upper roll B¹, of the first set is driven by spur wheels B⁵ from the lower roll B² which is in turn driven through reversing clutch mechanism from a transverse shaft E. The shaft E rotates unidirectionally and carries a bevel pinion E¹ in mesh with pinions F, G, free to rotate upon the lower roller shaft B⁴. Slidably upon a feather B⁶ on the shaft B⁴ is a slipper H provided at one end with a coned friction clutch member H¹ formed counterpart to a like member F¹ attached to and rotating with the pinion F, and at the other end bearing teeth H² counterpart to a dog clutch member G¹ attached to the pinion G. When the dog 100 clutch members are in engagement, a positive forward drive is transmitted through 105

the pinion G to the rollers B¹, B² which then rotate in the same direction as the delivery rolls A¹, A². When, however, the clutch is thrown over until the coned friction faces 5 contact, the drive takes place through the bevel pinion F and the direction of rotation of the rollers B¹, B² is therefore reversed.

The clutch operating mechanism employed in this example is shown diagrammatically 10 in Figure 3 and comprises a slide J located in guides J¹ and intermittently reciprocated by a link J² automatically actuated by any convenient means (not shown) from the machine to which the sliver is being fed. In 15 the slide J is a slotted track J³ terminating at each end in an out-turned portion J⁴. The track J³ is engaged by a pin J⁵ on one arm of a bell crank lever J⁶ fulcrumed at J⁷ and having its other arm operatively connected 20 to the slipper H of the clutch. When the sliver is to be diverted from one machine to another, the slide J is moved from left to right (Figure 3) through the intermediary of the link J². The pin J⁵ in following the 25 track J³ depresses the adjacent arm of the bell crank lever which in turn frees the forward driving clutch members H², G¹ and simultaneously throws the reversing friction members H¹, F¹ into engagement. The direction of rotation of the rolls B¹, B² is thus 30 reversed, causing a breakage in the sliver lap between these rolls and the succeeding pair D¹, D² which are continuously driven in the forward direction. During this momentary reversal, the sliver which is still being 35 delivered as before from the rolls A¹, A² forms a festoon, (as indicated by a dotted line in Figure 1) the length of which is determined by the speed at which the slide J is 40 caused to travel. The latter in completing its stroke to the right carries the pin J⁵ up the inclined end of the track J³ elevating the adjacent arm of the lever J⁶, which in turn frees the friction members and brings the dog clutch again into engagement. The 45 drive to the feeding rolls B¹, B² and D¹, D² is such that they rotate with a peripheral speed slightly greater—about 1 to 2%—than that of the delivery rolls A¹, A². This difference in speed allows the festoon formed 50 by the stoppage and reversal of the rolls B¹, B² to be entirely taken up before the sliver is again to be broken. The next break occurs on the movement of the slide J in the 55 opposite direction, that is from right to left, when the reversing mechanism is again brought into play in the same manner as before.

In order to ensure that the broken end of 60 sliver will not pass through the nip of the rolls B¹, B² and out of control thereof, a device limiting the actual distance through which these rolls may be reversed is provided. This device consists of a ratchet 65 wheel K carried by the upper roll shaft B³

and engaged by pawls K¹ hinged to a shrouded disc K² which is mounted on the shaft B² but free to rotate thereon. To the disc K² is attached a finger K³ located between two fixed stops K⁴, K⁵. When the rolls B¹, B² 70 are being driven in the forward direction, the finger K³ contacts with the stop K⁵ and the ratchet teeth ride over the pawls, so that the forward drive is in no way interfered with. When however the direction of rotation of the rolls is reversed, the pawls K¹ are 75 engaged and locked by the teeth of the ratchet, and the disc K² is consequently rotated solid with the latter until the finger K³ is intercepted by the stop K⁴ and the rolls 80 B¹, B² brought to rest. As the shaft B¹ with the clutch member H¹ is now held stationary while the pinion F with the clutch member F¹ is still driven, slip takes place between the two friction elements H¹, F¹, the former 85 of which is leather faced to allow of this. The clutch continues to slip until such time as the slide J completes its stroke and the forward driving clutch members are again brought into engagement. 90

What I claim is:—

1. In apparatus for delivering a continuous lap of sliver flowing at constant speed successively to a series of two or more machines, means for interrupting the flow and 95 for breaking the lap when the feed is to be diverted, comprising a pair of feeding rolls driven at a surface speed slightly greater than that of the lap, a gap bridged by the sliver and immediately preceding these rolls, 100 clutch controlled mechanism for driving the rolls in the forward and reverse directions, means for operating the clutch to cause momentary stoppage and reversal of the rolls, as and for the purposes set forth. 105

2. In apparatus for delivering a continuous lap of sliver flowing at constant speed successively to a series of two or more machines, means for interrupting the flow and 110 for breaking the lap when the feed is to be diverted, comprising a pair of feeding rolls driven at a surface speed slightly greater than that of the lap, a gap bridged by the sliver and immediately preceding these rolls, 115 clutch controlled mechanism for driving the rolls in the forward and reverse directions, means for operating the clutch to cause momentary stoppage and reversal of the rolls and adjustable independent means limiting the actual distance through which the rolls 120 are reversed, as and for the purposes set forth.

3. In the mechanism forming the subject matter of claim 1 hereof, bevel pinions free to rotate upon one of the feeding roller 125 shafts and driven in opposite directions from a transverse shaft, and a slidable clutch member mounted on a feather on the roller shaft and adapted on one side to be brought into positive engagement with the 130

pinion transmitting a forward drive to the rolls and on the other to be brought into frictional engagement with the reverse driving pinion, as set forth.

- 5   4. In the mechanism forming the subject-matter of claim 1 hereof, a slide intermittently reciprocated from the machine to which sliver is being fed; a slotted track in this slide with out-turned ends; and a bell 10 crank lever mounted on a fixed fulcrum, one arm of the lever carrying a pin engaging in the track, and the other arm operatively connected to the slideable member of the clutch; as and for the purposes set forth.
- 15   5. In the mechanism forming the subject-

matter of claim 1 hereof, a ratchet wheel carried on one of the roller shafts, a disc mounted on this shaft but free to rotate thereon, pawls hinged to the disc and so bearing on the ratchet as to ride over the latter when the rollers are forward driven, but to engage and lock the ratchet when the drive is reversed, and a finger attached to the disc and adjustably limited in travel by two fixed stops, as and for the purposes set forth.

In testimony whereof I have signed my name to this specification.

LOUIS GRIMOND MACINTYRE.
